Primary Examiner—Caron Veynar*Assistant Examiner*—Abraham Bahta(74) *Attorney, Agent, or Firm*—Arent Fox LLP(57) **CLAIM**

The ornamental design for a rectangle shaped vacuum pouch, as shown and described.

DESCRIPTION

FIG. 1 is a perspective view of a rectangular shaped vacuum pouch showing our new design;

FIG. 2 is a top view of the design shown in FIG. 1, wherein the bottom view is a mirror image thereof;

FIG. 3 is a front view thereof;

FIG. 4 is a rear view thereof; and,

FIG. 5 is a right side view of the design shown in FIG. 1, wherein the left side view is a mirror image thereof.

The broken lines shown in the drawings are for illustrative purposes only and form no part of the claimed design.
